UNITED STATES PATENT OFFICE.

JOHN FARREL, OF NEW YORK, N. Y.

DESIGN FOR A SAFE.

SPECIFICATION forming part of Design No. 16,806, dated July 20, 1886.

Application filed February 1, 1886. Serial No. 190,551. Term of patent 14 years.

To all whom it may concern:

Be it known that I, JOHN FARREL, of the city, county, and State of New York, have produced a new and original Design for a Safe, 5 whereof the following is a description, reference being had to the accompanying drawing, forming part of this specification.

A perspective view of the design is shown in the annexed drawing.

According to my design the body or shaft A is formed with plane sides and rounded vertical corners, as shown. The base B surrounds the shaft at the bottom, and consists of a plane band fitting and conforming to the shaft and

10 projecting beyond the same, and has accordingly plane sides and rounded vertical corners, as shown. The head or cornice C consists of an angular band, one flange thereof fitting and conforming to the shaft, and consequently has

plane sides and rounded vertical corners, as 20 shown, while the other flange is plane and fits upon the borders of the upper end of the body, as shown, and projects above the surface of the same.

I claim --

25 The design for a safe, consisting of a shaft, A, having plane sides and rounded vertical corners, base B, having plane sides and rounded vertical corners, and cornice C, having vertical plane sides with rounded vertical corners, 30 and horizontal plane border upon the upper end of the body surrounding a recessed panel, as shown and described.

JOHN FARREL.
